US00D931872S

(12) **United States Design Patent** (10) **Patent No.:** **US D931,872 S**
(45) **Date of Patent:** **** Sep. 28, 2021**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Brent Protzman**, Easton, PA (US);
Michelle L. Greene, Northampton, PA (US); **Erica L. Clymer**, Northampton, PA (US); **Jennifer Wong**, Breinigsville, PA (US); **Laura Marie Friedlander**, Harleysville, PA (US); **Joseph Roy Parks**, Emmaus, PA (US); **Edward J. Blair**, Telford, PA (US)

(73) Assignee: **Lutron Technology Company LLC**,
Coopersburg, PA (US)

(**) Term: **15 Years**

(21) Appl. No.: **29/678,309**

(22) Filed: **Jan. 28, 2019**

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design. The text illustrated in broken lines forms no part of the claimed design.

**1 Claim, 1 Drawing Sheet
(1 of 1 Drawing Sheet(s) Filed in Color)**

Related U.S. Application Data

continuation of application No. 29/583,433, filed on Nov. 4, 2016, now Pat. No. Des. 815,653, which is a continuation of application No. 29/525,147, filed on Apr. 27, 2015, now Pat. No. Des. 771,072.
